UNITED STATES PATENT OFFICE.

ISRAEL K. DIXON, OF JOHNSTOWN, PENNSYLVANIA.

SWITCH TONGUE.

Application filed November 26, 1924. Serial No. 752,368.

To all whom it may concern:

Be it known that I, ISRAEL K. DIXON, a citizen of the United States, and resident of Johnstown, in the county of Cambria and 5 State of Pennsylvania, have invented certain new and useful Improvements in Switch Tongues, of which the following is a specification.

This invention relates to tongue switches 10 and more particularly to the tongues for such switches, and has for its object the provision of a removable heel pin in the heel portion of the tongues, which pin may be manufactured separate from the tongue and, 15 therefore, have a better finish.

Another object is to provide a pin that may be readily replaced when broken, while the tongues heretofore made have been provided with integral pins which necessitated 20 replacement of the entire tongue when the pin was broken.

A further object is to provide a tongue switch having a novel construction, design and combination of parts hereinafter 25 described and illustrated in the accompanying drawings.

Heretofore switch tongues of the class to which this invention pertains have been formed with integrally cast heel pins, and 30 considerable difficulty has been experienced in getting a good finish on the pins, and also on the base of the tongues for the area adjacent to the pins, and also due to the fact that in casting such a small projection on 35 such a large mass it was difficult to cast perfect pins. A great percentage of the tongues cast were found to have defective pins and were necessarily scrapped.

The present invention entirely eliminates 40 the above difficulties and provides pins which may be either cast or machined separately and then removably mounted in the heel of the switch tongue.

In the drawings, Figure 1 is a top plan of 45 a portion of a switch structure embodying my invention.

Figure 2 is a section on the line II—II of Figure 1.

Figure 3 is a plan of the heel portion of 50 a switch tongue embodying my invention.

Figures 4 and 5 are sectional elevations on the lines IV—IV and V—V of Figure 3 respectively.

Figure 6 is a plan of the removable heel 55 pin.

Figure 7 is a sectional plan of the heel pin.

Referring more particularly to the drawings, the numeral 2 designates the body portion of a standard switch, provided with the usual tread and guard surfaces. The body 60 portion 2 is provided with an elongated recess or tongue bed 3 having an enlarged circular rear end 3^a to receive the heel 4 of the switch tongue 5.

The heel 4 is provided with a cylindrical 65 recess 6 having a restricted elongated opening 7 entering from the bottom face of the heel portion 5. The recess 6 being of materially greater diameter than the width of the opening 7, flanges 8 are provided on each 70 side of the opening.

A heel pin A having an elongated head member 9, shank or stem portion 10 and a base portion 11 is adapted to be inserted 75 through the opening 7 into the recess 6 and locked therein.

The head member 9 has its ends projecting materially beyond the shank or stem 10 of the pin, forming retaining lugs 12. In operation, the head 9 of the pin is adapted 80 to be passed through the opening 7 into the recess 6 and the pin given a half turn so that the lugs 12 will overlie the flanges 8, thus holding the pin in position. After the pin is thus mounted in the recess it may be locked 85 against accidental displacement by filling the recess 6 with spelter or other soft metal 14 which may be readily removed if it is desired to replace the pin when it becomes 90 broken or worn.

The pin A is adapted to hold the tongue in perfect bearing in the heel receiving portion 3^a of the tongue bed 3 under conditions of snow, ice or mud.

The pin A is adapted to project through 95 an orifice 15 in the portion 3^a of the bed 3, into a recess 16 below the tongue bed. Mounted within this recess 16 is a lever 17, which is fulcrumed on a projection 18, on the switch body 2. One end of a lever 17, 100 is provided with a fork 19, and the opposite end 20 is provided with a boss which is threaded to receive a screw 21 having a jam nut 22. The forked end 19 of the lever 17 is engaged around the shank or stem 10 of 105 the pin A.

When the parts are assembled the screw 21 is screwed down to its proper place of adjustment and locked by the jam nut 22. As 110 will be readily understood from the drawings, the screw 21 has a tendency to raise the one end of the lever 17, thereby depress-

ing the forked end 19, and with it the heel 4 of tongue 5.

The advantages of having the pin A removable so that it may be formed separate 5 from the tongue 5 will be readily appreciated by those skilled in the art, since it eliminates one of the greatest causes of imperfect castings.

While I have shown and described only 10 one embodiment of my invention, it will be understood that I do not wish to be limited thereto, since various modifications may be made without departing from the scope of my invention as defined in the appended 15 claims.

I claim—

1. A switch tongue having a heel portion provided with a recess having a reduced opening extending through the bottom face 20 of said heel portion, and a tongue securing pin having a head portion adapted to enter said reduced opening and to engage the bottom wall of said recess when given a half turn.

2. A switch tongue having a heel portion 25 provided with a recess having a reduced opening extending through the bottom face of said heel portion, a tongue securing pin having a head portion adapted to enter said reduced opening and to engage the bottom wall of said recess when given a half turn, and a filling of metal adapted to prevent accidental removal of said pin.

3. A switch tongue having a heel portion provided with a recess having an elongated 30 reduced opening through the bottom face of said heel portion, said recess being enlarged beyond the size of said opening to provide flanges around said opening, a tongue securing pin having a head portion 40 adapted to enter said reduced opening and to overlie said flanges when said pin is given a half turn, and removable means for locking said pin against accidental displacement.

In testimony whereof, I have hereunto set my hand.

ISRAEL K. DIXON.
